[57] CLAIM

The ornamental design for a pitcher and lid assembly, as shown and described.

DESCRIPTION

FIG. 1 is a right side elevational view of a pitcher and lid assembly showing our new design;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a top plan view of a pitcher and lid assembly, showing a second embodiment of our new design. All other view of the second embodiment are identical to FIGS. 1-3 and 5.

FIG. 2

FIG. 1

FIG. 4

FIG. 3

FIG. 5**FIG. 6**
